UNITED STATES PATENT OFFICE.

JOHN E. TALLEY AND JOHN WILMER THOMPSON, OF PHILADELPHIA, PENNSYLVANIA.

DISPLAY APPARATUS.

1,334,817.

Specification of Letters Patent. Patented Mar. 23, 1920.

Application filed August 6, 1917. Serial No. 184,717.

To all whom it may concern:

Be it known that we, JOHN E. TALLEY and JOHN WILMER THOMPSON, citizens of the United States, and residents of Philadelphia, Pennsylvania, have invented certain Improvements in Display Apparatus, of which the following is a specification.

Our invention relates to merchandise display cabinets for retail stores, salesrooms and the like, of the type for instance as those disclosed in our pending application, filed April 24, 1917, Serial No. 164,211. The object of our present invention is to improve certain details of construction in devices of this kind; our present improvements involving the use of a special form of traveling carriage, and a depending carrier or supporting frame rotatably mounted with respect to said traveling carriage.

These and other features of our invention are more fully described hereinafter reference being had to the accompanying drawings, in which:

Figure 1, is a sectional elevation of a merchandise display cabinet showing a traveling and rotatable supporting structure embodying our present invention.

Fig. 2, is an elevation on a larger scale, partly in section, of a portion of the structure shown in Fig. 1.

Fig. 3, is a plan view of a part of the structure shown in Fig. 2.

Figs. 4 and 5, are views similar to Fig. 2, illustrating other forms of traveling and rotatable supporting structures within the scope of our invention, and

Fig. 6, is a plan view of the structure shown in Fig. 5.

In the drawings herewith, 1 may represent a glass-walled cabinet of the usual type, such for instance as those illustrated in our prior application, having suitably mounted within the same, tracks 2, 2, which may be of channel sections of any suitable type. In this view these tracks are shown at the top of the cabinet, with the supporting frame depending therefrom, but they may be mounted at the bottom of the cabinet, with the supporting frame disposed for rotation above the same without departing from our invention. Adapted to the tracks 2 are the wheels 3 of a traveling carriage which, in the present instance, may comprise a plate 4, having straps or other suitable connections 5 secured thereto for the reception of

the axles carrying said wheels; said plate having centrally thereof a suitable form of ball-bearing 7, which may be held in position with respect to the plate 4 by clamping members or clips 8, disposed above and below said plate 4, and secured thereto by bolts 9 and nuts 10, or any other suitable form of fastening means.

The ball bearing may comprise an outer ring or collar 11 forming a pair of ball cups or races at top and bottom of the same, with internally disposed cones 12, and two sets of balls 13 disposed between said cones and the outer cupped sleeve. These several parts may be carried by an internally threaded sleeve or collar 14, externally threaded at its ends with nuts 15 thereon whereby said bearing may be properly positioned on said sleeve. Threaded into said sleeve or collar 14 and depending therefrom and from the ball-bearing, is a tubular member 16 which is held in position with respect to the collar 14, by nuts 17 and 18.

At the lower end of the tubular member 16 is a sleeve or collar 19 which may be threaded thereon and provided with outwardly and upwardly extending struts 20 connected at their outer ends to an annular rail or bar 21, from which garments or other objects, or any supports therefor may be hung; said rail or bar 21 being also connected to a series of spokes 22 radiating from a collar or ring 23 on the tubular member 16 and disposed just below the ball-bearing. The ring or collar 23 may be permanently secured to the tubular member 16 if desired, and the lower end of the latter may have a cap 24, threaded thereon and engaging the collar 19, and in such instance affording a lock for such collar.

In Fig. 4, we have illustrated a slightly modified arrangement in which the plate 4^a of the carriage frame is shown as cupped at the center as indicated at 8^a to receive the ball-bearing, (which may be of the same type as that illustrated in Fig. 2,) and carries an upper cupped member 8^b to hold such ball-bearing in place; the same being secured to the plate 4^a by screw bolts 9^a. Or, if desired, the clips 8 shown in Fig. 2, may be employed to hold the bearing in place with the construction shown in Fig. 4.

In this construction, the supporting frame comprising the struts 20, rail or bar 21 and spokes 22 carried by a collar or ring 23, is

substantially like that shown in Figs. 1 and 2, but the plate 4^a is preferably provided with a series of struts or braces 25 disposed between the same and a collar 26 mounted 5 on the tubular member 16, above the collar 23 carrying the spokes 22.

In the arrangement shown in Figs. 5 and 6, we provide a carriage of a slightly different character, the frame of which may 10 be a single member 4^b, substantially cruciform in outline, having a thick hub 30, and having wheels 3^a adapted to the rails or track 2^a, and to which a depending stem or tubular member 16^a is centrally secured in 15 fixed position. The tubular member is adapted to the hub 30 and may be held in a fixed position with reference to the frame by means of suitable nuts 17^a and 18^a. In this arrangement, the depending member 20 carries ball bearings 31 and 32, of a different type, disposed at the upper and lower portions of the depending member 16^a, and the supporting frame is secured to a sleeve 33 positioned to rotate on the depending 25 member, which forms an extended bearing therefor, between the ball bearings 31 and 32. In this construction, the struts may be secured to the arms 34 of a ring 35 carried by the sleeve 33 just above the lower bearing; screws 36 being employed, if desired, and their outer ends, which underlie the 30 spokes, may be secured thereto by screws 37.

Traveling carriages of the type illus-

trated herewith and fitted with supporting frames of the type also illustrated may be 35 used, of course, with the cabinet structure illustrated in our former application, which is shown with buffer pads provided to take the shock at the ends of its movements. Either form of structure may be employed 40 at the bottom of the cabinet as well as at the top; any necessary or suitable changes being made in the position occupied by the ball-bearings, and when so disposed the carriages will support an upwardly extending 45 framework of any suitable character, arranged to carry shelves or the like, as may be desired.

We claim:

The combination, with a goods display 50 cabinet, comprising a casing, a trackway mounted in said casing, and a wheeled carriage adapted to said trackway, of a frame comprising a stem centrally depending from said carriage, an annular supporting rail, 55 spokes horizontally disposed between the stem and rail, a plurality of upwardly and outwardly extending struts connected to said annular rail, a ring at the lower ends of said struts surrounding the lower end of 60 said depending stem, connections between the spokes and struts at the rail, and a ball bearing supported by said stem below the ring connected to the struts.

JOHN E. TALLEY.
J. WILMER THOMPSON.
